UNITED STATES PATENT OFFICE

2,668,457

HAND BRAKE FOR RAILWAY CARS

Frank E. Bretz, Jr., Oak Park, Ill., assignor to
Ajax-Consolidated Company, Chicago, Ill., a
corporation of Illinois

Application August 5, 1950, Serial No. 177,804

8 Claims. (Cl. 74—505)

1

This invention relates, generally, to brakes, and it has particular relation to hand brakes for railway cars.

Among the objects of this invention are: To provide for applying the brakes of a railway car by turning a member, such as a hand wheel, in one direction, and for releasing the brakes by applying torque to turn the member in the opposite direction; to accomplish this by interposing a friction clutch between the member or hand wheel and a drum on which a chain, connected to the brake rigging, is wound; to operate the friction clutch by cooperating cam surfaces; to position the cam surfaces so that a wide range of angles of inclination can be employed whereby there is a wide range in the torque required to rotate the hand wheel to apply and release the brakes; to employ a floating cam plate between the cam surfaces and a clutch face for developing and controlling the friction connection between the hand wheel and the chain winding drum; to place the clutch face on a ratchet wheel and arrange for preventing rotation thereof in one direction; and to position the friction clutch mechanism between the ratchet wheel and the pinion which drives the main gear wheel attached to the chain winding drum.

Other objects of this invention will, in part, be obvious and in part appear hereinafter.

This invention is disclosed in the embodiment thereof shown in the accompanying drawings, and it comprises the features of construction, combination of elements and arrangement of parts which will be exemplified in the construction hereinafter set forth and the scope of the application of which will be indicated in the appended claims.

For a more complete understanding of the nature and scope of this invention, reference may be had to the following detailed description, taken together with the accompanying drawings, in which:

Figure 1 is a view in front elevation, at a reduced scale, of a hand brake mechanism in which the present invention is embodied, the hand wheel being broken away in order to illustrate the details of construction of the casing and of the trip handle;

Figure 2 is a view, at an enlarged scale, partly in side elevation and partly in section showing certain of the details of construction of the brake mechanism, the hand wheel again being shown partially in order not to obscure certain details of construction;

2

Figure 3 is a longitudinal sectional view taken generally along the line 3—3 of Figure 2, the pawl and trip handle being omitted;

Figure 4 is a view at an enlarged scale taken along the line 4—4 of Figure 3 and looking in the direction of the arrows showing the pinion and the reentrant camming surfaces thereon;

Figure 5 is a detail sectional view, at an enlarged scale, taken along the line 5—5 of Figure 3 and looking in the direction of the arrows;

Figure 6 is a detail sectional view, at an enlarged scale, taken generally along the line 6—6 of Figure 3 and looking in the direction of the arrows; and

Figure 7 is a view, in side elevation, of the pinion and cam plate in spaced apart relationship with the respective camming surfaces in alignment.

Referring now particularly to Figure 1 of the drawings, it will be observed that the reference character 10 designates, generally, a hand brake mechanism in which the present invention is embodied. The hand brake mechanism 10 includes a case, shown generally at 11, which comprises a cover 12 having an outwardly extending flange 13 that overlies a back plate 14, Figure 3, which encloses the rear side of the cover 12. The flange 13 and underlying portion of the back plate 14 are provided for mounting the hand brake mechanism 10 flatwise against the side or end of a railway car as will be understood readily. A hand wheel 15 is carried by the hand brake mechanism 10 for the purpose of applying the brakes. In accordance with the present invention the hand wheel 15 also is positively operated by the brakeman for releasing the brakes. Also mounted on the front side of the cover 12 is a trip handle 16. As will appear hereinafter, the trip handle 16 can be omitted. Connection to the brake rigging of a railway car is provided by means of a chain 17.

As illustrated more clearly in Figure 3, the chain 17 is secured by a pin 19 to a chain winding drum 20 that is rotatably mounted about a stationary shaft 21 which is mounted at its ends on the cover 12 and back plate 14 respectively. Formed integrally with the chain winding drum 20 is a main gear wheel 22 which has gear teeth 23 on its periphery, that mesh with gear teeth 24 of a pinion that is shown generally at 25 and is rotatably and non-slidably mounted on a pinion bearing portion 26 of a hand wheel shaft that is shown, generally, at 27. It will be observed that the axis of rotation of the hand

wheel shaft 27 is parallel to the axis of rotation of the chain winding drum 20 and of the main gear wheel 22. The hand wheel shaft 27 is mounted at one end on the cover 12 by a bearing casting 28. At its other end the shaft 27 is journaled in a bearing bushing 29 that is carried by an inturned flange 30 of the back plate 14. Near this end of the shaft 27 a split ring 31 is located in a suitable annular groove to prevent endwise movement of the pinion 25. The split ring 31 is held in place by a bearing sleeve 32 that has a press fit with the shaft 27 and itself is journaled in the bearing bushing 29.

In accordance with this invention the hand wheel 15 is connected to the chain winding drum 20 by means of a friction clutch which is indicated, generally, at 35. As will appear hereinafter, the construction of the friction clutch 35 is such that a positive rotation of the hand wheel 15 is required not only for applying the brakes but also for releasing them.

As a part of the friction clutch 35 a ratchet wheel 36 is employed which is rotatably mounted on the shaft 27 by a bearing bushing 37. The bearing bushing 37 extends over a circular ratchet wheel bearing portion 38 of the shaft 27 so that, except as hereinafter provided, the ratchet wheel 36 is freely rotatable on the shaft 27.

The ratchet wheel 36 has ratchet teeth 39 at its periphery with which a ratchet pawl 40, Figure 2, cooperates to prevent reverse rotation. It will be understood that other equivalent means can be employed in lieu of the ratchet teeth 39 and ratchet pawl 40 for preventing reverse rotation of the ratchet wheel 36. The ratchet pawl 40 is pivoted at 41 and is arranged to swing in a clockwise direction so that it is always biased toward the ratchet wheel 36. In some instances it may be desirable to force the ratchet pawl 40 toward the ratchet wheel 36. For this purpose a hold down arm 42 can be used and arranged to bear against the rear side of the ratchet pawl 40. The arm 42 is carried by a hold down shaft 43 which is journaled in the cover 12 and back plate 14 as illustrated more clearly in Figure 3. The shaft 43 has a shank 44 at its forward end for receiving the trip handle 16. An arm 45, formed integrally with the shaft 43, bears against the underside of the cover 12 and prevents outward endwise movement of the shaft 43. As described hereinbefore, the hold down arm 42, shaft 43, and trip handle 16 can be omitted since their only function is to assist the biasing action applied to the ratchet pawl 40 for holding it in engagement with the ratchet wheel 36.

As shown in Figure 3 a collar 48 is formed integrally with the shaft 27 and serves to prevent endwise movement of the bearing bushing 37 and thereby endwise movement of the ratchet wheel 36. As here shown, the ratchet wheel 36 has a flat surface or clutch face 49 on its left hand side with which an annular friction plate 50 engages. The friction plate 50 is formed of material that is used for facing friction clutches or the like. The other side of the friction plate 50 bears against a flat surface or clutch face 51 formed on the right hand end of a floating cam plate 52. The cam plate 52 is slidably and non-rotatably mounted on the shaft 27. For this purpose a cam plate bushing 53, Figure 5, is employed and it is slidable along a non-circular bearing portion 54 of the shaft 27 as here illustrated. The bearing portion 54 includes a flat surface 55 with which

the cam plate bushing 53 and floating cam plate 52 conform.

With a view to moving the floating cam plate along the non-circular bearing surface 54 toward the ratchet wheel 36 so as to provide driving engagement therebetween through the annular friction plate 50, protuberant camming surfaces 56, Figure 7, are provided on the side of the floating cam plate opposite the clutch face 51. These protuberant camming surfaces 56 also are illustrated in Figure 5. Cooperating with the protuberant camming surfaces 56 are reentrant camming surfaces 57, Figures 4 and 7, that are carried by the pinion 25 on the side facing the hand wheel 15. The cooperating camming surfaces 56 and 57 serve to energize the friction clutch 35 in a manner to be described presently.

The shaft 27 includes a hand wheel attaching portion 61 which projects beyond the cover 12, as shown in Figure 3, for receiving the hand wheel 15. A lock nut 62, threaded on the outer end of the portion 61, serves to hold the hand wheel 15 in position.

As pointed out hereinbefore, the floating cam plate 52 is keyed to the shaft 27 so that it is non-rotatable with respect thereto but it is free to move in either axial direction. When it is desired to apply the brakes, the hand wheel 15 is rotated in a clockwise direction as viewed in Figures 1 and 2 of the drawings. When the hand wheel 15 is rotated in this direction to apply the brakes, the camming surfaces 56 on the floating cam plate 52 move slightly relative to the reentrant camming surfaces 57 on the pinion 25 through an extent which depends, in part, on the tension of the chain 17. This relative movement tends to separate the floating cam plate 52 from the pinion 25. Since the pinion 25 is prevented from moving to the left by the split ring 31, the only axial movement that can take place is the movement of the floating cam plate 52 to the right toward the ratchet wheel 36. This movement forces the flat surface or clutch face 51 of the floating cam plate 52 into closer engagement with the adjacent surface of the friction plate 50. In turn the opposite face of the friction plate 50 is brought into closer engagement with the flat surface or clutch face 49 of the ratchet wheel 36. Since the ratchet wheel 36 cannot move axially because of the collar 48, the net effect of the movement of the floating cam plate 52 to the right is to place it in better frictional driving engagement with the ratchet wheel 36. In this manner the stresses incident to the operation of the friction clutch 35 are self contained and, as the hand wheel 15 is rotated in the clockwise direction, the tension of the chain 17 is applied to the whole unit which, in effect, constitutes a solid connection between the hand wheel 15 and the chain winding drum 20. This direct connection then will take up the slack in the brakes and apply them with the braking force that is required to the extent that the hand wheel 15 is rotated. As the ratchet wheel 36 rotates in the same direction, the ratchet pawl 40 ratchets over the teeth 39 and acts to hold it in any position to which it may be rotated. On cessation of application of torque to the hand wheel 15, the brakes remain set to the extent indicated.

When it is desired to release the brakes, the hand wheel 15 is rotated in a counterclockwise direction. The ratchet pawl 40 prevents reverse rotation of the ratchet wheel 36 when this takes place. Since the floating cam plate 52 is ro-

tatable with the shaft 21, when the hand wheel 15 is rotated in a counterclockwise direction it will rotate slightly with respect to the pinion 25 so that the camming surfaces 56 thereon move slightly downwardly with respect to the reentrant camming surfaces 57 on the pinion 25. Because of this relative movement of the camming surfaces 56 and 57, the pressure applied to the friction plate 50 is relieved somewhat which permits slight rotation of the shaft 21. The tension applied through the chain 17 by the brake rigging with the brakes set immediately tends to turn the pinion 25 in such a direction that will cause the reentrant camming surfaces 57 to climb over the protuberant camming surfaces 56 and thus effect a slight movement of the floating cam plate 52 to the right, as viewed in Figure 3. This retightens the friction clutch 35 but at a point where the tension in the chain 17 or the force setting of the brake rigging has been decreased. As the hand wheel 15 is rotated further in the counterclockwise direction, a series of loosening and tightening of the friction clutch 35 takes place in the manner described so that the tension in the chain 17 or load applied thereto by the brake rigging is gradually and uniformly released. Since the continued rotation of the hand wheel 15 by external torque in the counterclockwise direction is required in order to release the brakes, it follows that any given brake setting will be maintained merely by ceasing to apply further counterclockwise torque to the hand wheel 15.

By placing the camming surfaces 56 and 57 in the locations illustrated in the drawings and described, considerable latitude is provided in the angle of inclination of these camming surfaces. Specifically, the angle of inclination is indicated at 64 for the camming surfaces 56 in Figure 7 and the angle of inclination 65 for the camming surfaces 57 can be varied in the initial design depending upon several design factors and operating conditions which are required to be met. It is possible to determine the holding power required for the friction clutch 35 for all practical purposes and to use such angles of inclination as not to exceed substantially this holding power. This permits the use of lower forces on the annular friction plate 50 which, in turn, permits the release of the brakes with considerably less effort applied to the hand wheel 15.

As indicated various angles of inclination 64 and 65 can be employed. Tests have shown that these angles may vary from 7° to 30°. While the angles of inclination 64 and 65 may be identical, it may be desirable to use different angles depending upon the forces and other design factors involved. While two protuberant camming surfaces 56 and two cooperating reentrant camming surfaces 57 have been illustrated, it will be understood that additional cooperating camming surfaces can be employed if required. Also, if desired, a second friction plate 50 can be provided on the opposite side of the ratchet wheel 36 and an extension of the collar 48.

In applying the brakes the use of the frictional forces transmitted through the friction clutch 35 are not required. This is due to the fact that the cam plate 52 is keyed to the shaft 21 and the camming surfaces 56 and 57 are so related that they cannot move completely past each other. Thus it is always possible to apply the brakes even though there may be excessive lubrication of the friction plate 50 which might cause some slip-

page of the friction clutch 35. Such slippage would be effective only after the brakeman releases the hand wheel 15.

Since certain further changes can be made in the foregoing construction and different embodiments of the invention can be made without departing from the spirit and scope thereof, it is intended that all matter shown in the accompanying drawings and described hereinbefore shall be interpreted as illustrative and not in a limiting sense.

What is claimed as new is:

1. In a hand brake mechanism, the combination with a rotary chain winding drum and a main gear wheel of a rotatable hand wheel shaft, a hand wheel fast on said hand wheel shaft, a pinion rotatably and non-slidably mounted on said hand wheel shaft and engaging said gear wheel, a clutch plate rotatably mounted on said hand wheel shaft, means on said hand wheel shaft preventing movement of said clutch plate away from said pinion, means cooperating with said clutch plate and preventing rotation thereof in a brake releasing direction, a cam plate non-rotatably and slidably mounted on said hand wheel shaft between said pinion and said clutch plate and arranged to have frictional driving connection with the latter and cooperating inclined plane means carried respectively by said pinion and said cam plate for moving the latter toward and into positive driving connection with said clutch plate when said manually rotatable means is rotated in one direction to apply the brakes and allowing said cam plate to move away from and out of positive driving connection with said clutch plate when said manually rotatable means is rotated in the opposite direction to release the brakes.

2. The invention, as set forth in claim 1, wherein the clutch plate is provided with ratchet teeth and a pawl cooperates therewith to prevent rotation of the former in one direction.

3. The invention, as set forth in claim 1, wherein the angle of inclination of the inclined plane means ranges from 7° to 30°.

4. In a hand brake mechanism, the combination with a rotary chain winding drum and a main gear wheel of a hand wheel shaft mounted for rotation about an axis parallel to the axis of rotation of said chain winding drum and main gear wheel, said hand wheel shaft having a pinion bearing portion at one end, a non-circular bearing portion adjacent said pinion bearing portion, a ratchet wheel bearing portion adjacent said non-circular bearing portion, and a hand wheel attaching portion at the other end, a hand wheel fast on said hand wheel attaching portion, a pinion rotatably mounted on said pinion bearing surface, a floating cam plate slidably mounted on said non-circular bearing portion, a ratchet wheel rotatably mounted on said ratchet wheel bearing portion and having a clutch face on the side facing said pinion means on said hand wheel shaft preventing movement of said ratchet wheel away from said pinion, a pawl cooperating with said ratchet wheel to prevent reverse rotation thereof, and cooperating camming means carried respectively by said pinion and said cam plate for moving the latter toward and into positive driving connection with said clutch face and allowing movement of said cam plate away and out of driving connection therewith, said camming means cooperating so that on rotation of said hand wheel in one direction with an unwinding torque applied to said

chain winding drum said cam plate is moved laterally away from said pinion and toward said ratchet wheel and thereby has driving connection with said clutch face to rotate the same and simultaneously said chain winding drum is rotated in the winding direction, said camming means also cooperating so that on rotation of said hand wheel in the opposite direction while said pawl holds said ratchet wheel stationary said cam plate is moved laterally away from said ratchet wheel and clutch face and toward said pinion thereby permitting the latter to turn under the influence of said unwinding torque and effect a corresponding release of the brakes.

5. In a hand brake mechanism the combination with a rotary chain winding drum and a main gear wheel of: a hand wheel shaft mounted for rotation about an axis parallel to the axis of rotation of said chain winding drum and main gear wheel, said hand wheel shaft having a pinion bearing portion at one end, a non-circular bearing portion adjacent said pinion bearing portion, a ratchet wheel bearing portion adjacent said non-circular bearing portion, and a hand wheel attaching portion at the other end; a hand wheel fast on said hand wheel attaching portion, a pinion rotatably mounted on said pinion bearing surface and having at least one reentrant camming surface on the side facing said hand wheel, a floating cam plate slidably mounted on said non-circular bearing portion and having a protuberant camming surface on one side engaging said reentrant camming surface, a ratchet wheel rotatably mounted on said ratchet wheel bearing portion and having a clutch face arranged to have frictional driving connection with the other side of said cam plate, means on said hand wheel shaft preventing movement of said ratchet wheel away from said pinion, and a pawl cooperating with said ratchet wheel to prevent reverse rotation thereof, said camming surfaces cooperating so that on rotation of said hand wheel in one direction with an unwinding torque applied to said chain winding drum said cam plate is moved laterally away from said pinion and toward said ratchet wheel and thereby has driving connection with said clutch face to rotate the same and simultaneously said chain winding drum is rotated in the winding direction, said camming surfaces also cooperating so that on rotation of said hand wheel in the opposite direction while said pawl holds said ratchet wheel stationary said cam plate is moved laterally away from said ratchet wheel and toward said pinion thereby permitting the latter to turn under the influence of said unwinding torque and effect a corresponding release of the brakes.

6. In a hand brake mechanism, the combination with a rotary chain winding drum and a main gear wheel of: a hand wheel shaft mounted for rotation about an axis parallel to the axis of rotation of said chain winding drum and main gear wheel, said hand wheel shaft having a pinion bearing portion at one end, a non-circular bearing portion adjacent said pinion bearing portion, a ratchet wheel bearing portion adjacent said non-circular bearing portion, and a hand wheel fast on said hand wheel attaching portion, a pinion rotatably mounted on said pinion bearing surface and having at least one reentrant camming surface on the side facing said hand wheel, a floating cam plate slidably mounted on said non-circular bearing portion and having a protuberant camming surface engaging said reentrant camming surface, a ratchet wheel rotat-

ably mounted on said ratchet wheel bearing portion, means on said hand wheel shaft preventing movement of said ratchet wheel away from said pinion, a friction plate between said cam plate and said ratchet wheel, and a pawl cooperating with said ratchet wheel to prevent reverse rotation thereof, said camming surfaces cooperating so that on rotation of said hand wheel in one direction with an unwinding torque applied to said chain winding drum said cam plate is moved laterally away from said pinion and toward said ratchet wheel and thereby has driving connection with the latter through said friction plate to rotate the same and simultaneously said chain winding drum is rotated in the winding direction, said camming surfaces also cooperating so that on rotation of said hand wheel in the opposite direction while said pawl holds said ratchet wheel stationary said cam plate is moved laterally away from said ratchet wheel and toward said pinion thereby permitting the latter to turn under the influence of said unwinding torque and effect a corresponding release of the brakes.

7. In a hand brake mechanism, the combination with a rotary chain winding drum and a main gear wheel of: a hand wheel shaft mounted for rotation about an axis parallel to the axis of rotation of said chain winding drum and main gear wheel, said hand wheel shaft having a pinion bearing portion at one end, a non-circular bearing portion adjacent said pinion bearing portion, a ratchet wheel bearing portion adjacent said non-circular bearing portion, a collar integral with said shaft adjacent said ratchet wheel bearing portion, and a hand wheel attaching portion at the other end; a hand wheel fast on said hand wheel attaching portion, a pinion rotatably mounted on said pinion bearing portion and having at least one reentrant camming surface on the side facing said hand wheel, a floating cam plate slidably mounted on said non-circular bearing portion and having a protuberant camming surface engaging said reentrant camming surface, a ratchet wheel rotatably mounted on said ratchet wheel bearing portion and held against endwise movement along said hand wheel shaft by said collar thereon, a friction plate between said cam plate and said ratchet wheel, and a pawl cooperating with said ratchet wheel to prevent reverse rotation thereof, said camming surfaces cooperating so that on rotation of said hand wheel in one direction with an unwinding torque applied to said chain winding drum said cam plate is moved laterally away from said pinion and toward said ratchet wheel and thereby has driving connection with the latter through said friction plate to rotate the same and simultaneously said chain winding drum is rotated in the winding direction, said camming surfaces also cooperating so that on rotation of said hand wheel in the opposite direction while said pawl holds said ratchet wheel stationary said cam plate is moved laterally away from said ratchet wheel and toward said pinion thereby permitting the latter to turn under the influence of said unwinding torque and effect a corresponding release of the brakes.

8. In a hand brake mechanism, the combination with a rotary chain winding drum and a main gear wheel of: a hand wheel shaft mounted for rotation about an axis parallel to the axis of rotation of said chain winding drum and main gear wheel, said hand wheel shaft having a pinion bearing portion at one end, a non-circular bearing portion adjacent said pinion bearing portion, a ratchet wheel bearing portion adjacent said non-circular bearing portion, a collar integral with said shaft adjacent said ratchet wheel bearing portion, and a hand wheel attaching portion at the other end; a hand wheel fast on said hand wheel attaching portion, a pinion rotatably mounted on said pinion bearing portion and having at least one reentrant camming surface on the side facing said hand wheel, a floating cam plate slidably mounted on said non-circular bearing portion and having a protuberant camming surface engaging said reentrant camming surface, a ratchet wheel rotat-

cular bearing portion adjacent said pinion bearing portion, a ratchet wheel bearing portion adjacent said non-circular bearing portion, a collar integral with said shaft adjacent said ratchet wheel bearing portion, and a hand wheel attaching portion at the other end; a hand wheel fast on said hand wheel attaching portion, a pinion rotatably mounted on said pinion bearing portion and having at least one reentrant camming surface on the side facing said hand wheel, a floating cam plate slidably mounted on said non-circular bearing portion and having a protuberant camming surface engaging said reentrant camming surface, a ratchet wheel rotatably mounted on said ratchet wheel bearing portion and held against endwise movement along said hand wheel shaft by said collar thereon, a friction plate between said cam plate and said ratchet wheel, a pawl cooperating with said ratchet wheel to prevent reverse rotation thereof, a hold down shaft mounted for rotation about an axis parallel to the axis of rotation of said hand wheel shaft, a handle fast on said hold down shaft, and a hold down arm on said hold down shaft for engaging said pawl and holding it in engagement with the teeth of said ratchet wheel, said camming surfaces cooperating so that on rotation of said hand wheel in one direction with an unwinding torque applied to

said chain winding drum said cam plate is moved laterally away from said pinion and toward said ratchet wheel and thereby has driving connection with the latter through said friction plate to 5 rotate the same and simultaneously said chain winding drum is rotated in the winding direction, said camming surfaces also cooperating so that on rotation of said hand wheel in the opposite direction while said pawl holds said ratchet wheel stationary said cam plate is moved laterally away from said ratchet wheel and toward said pinion thereby permitting the latter to turn under the influence of said unwinding torque and effect a corresponding release of the brakes.
